UNITED STATES PATENT OFFICE.

JOSEPH F. GARDNER, OF KANSAS CITY, MISSOURI.

PNEUMATIC FOUNTAIN-PEN.

1,307,195.

Specification of Letters Patent. Patented June 17, 1919.

Application filed April 29, 1918, Serial No. 231,305. Renewed May 1, 1919. Serial No. 294,095.

To all whom it may concern:

Be it known that I, JOSEPH F. GARDNER, a citizen of the United States, residing at Kansas City, in the county of Jackson and 5 State of Missouri, have invented a new and useful Pneumatic Fountain-Pen, of which the following is a specification.

My invention relates to pneumatic fountain pens in which the gravity of the fluid 10 is retarded by air, and the object of my invention is to provide a simple and efficient fountain pen which shall automatically and adequately supply fluid to the pen in the light or heavy writing, drawing or marking, 15 to obtain uniform shade of ink in the writing, drawing or marking, and to provide a fountain with capacity for a body of fluid having gravity to crowd confined air to obtain high sensibility in the pen.

20 I attain these objects and other advantages by the mechanism and combination of parts illustrated in the accompanying drawing, in which—

Figure 1, is a perspective view of a fountain pen combining my invention, and showing the fountain at the upper end of the pen;

Fig. 2, is a sectional view of the pen, taken on the line 2—2, in Fig. 1, and showing my complete invention;

30 Fig. 3, is a transverse section of the same, taken on the line 3—3, in Fig. 1;

Fig. 4, is a transverse section of the same, taken on the line 4—4, in Fig. 1, and

Fig. 5, is a transverse section of the same, 35 taken on the line 5—5, in Fig. 1.

Similar numerals of reference refer to corresponding parts throughout the several views.

1, is a rubber bulb of suitable proportion 40 to contain a body of fluid ink and having a neck 2, hermetically secured in a cup 3, formed in the upper end of a fitting 4, the lower end portion of the fitting being reduced a little and provided with external 45 screw threads adapted to receive the internal screw threads at the upper end of a hard rubber tube 5. A hole is bored longitudinally through the fitting and opens through the bottom of the cup 3, in which hole the upper end of a small flexible tube 6, is secured. The lower end of the tube 5, is provided with internal screw threads adapted to receive the screw end of a hard rubber tube 7. A plug 8, is hermetically secured in 50 the upper end of the tube 7, and a hole is

apertured through the plug, in which hole a small flexible tube 9, is secured by its upper end. The inner diameters of the tubes 6 and 9, are dimensioned to limit their capacity, so that fluid ink shall gravitate from the 60 fountain through the same in very limited quantity. The tubes 6 and 9, are extended downwardly in their respective chambers to a suitable distance below the middle of the chambers, so that when fluid ink in the 65 chambers shall rise above the lower ends of the tubes, the air in the chambers will be confined and crowded upward by the gravity of the fluid ink until the contending forces are equalized and, thereafter, wastage of the 70 ink incident to writing be automatically supplied by the fountain whenever the equilibrium established by the contending forces is disturbed. The lower end of the tube 7, is provided with internal screw threads adapted 75 to receive the screw end of a nipple 10, having its lower end beveled to receive a pen point 11, having the customary aperture 12. A plug 13, is hermetically secured in the nipple 10, and is extended outwardly of the nipple a suitable distance to support the pen point. A channel 14, is formed longitudinally in the upper surface of the plug 13, the outer end of the channel terminating at a point substantially below the opening in 80 the pen point, the inner end thereof opening into tube 7. The capacity of the channel 14, is preferably limited to the identical capacity of the small tubes 6 and 9. All joints and connections are made absolutely air 85 tight, so that the fountain 1, the chamber 15, in tube 5, and the chamber 16, in tube 7, will not communicate with atmosphere when the pen is operative.

To operate my pen, the bulb or fountain 90 1, is removed from the pen by unscrewing it from the tube 5, and the tube 6, immersed into a supply of fluid ink, when the bulb is pressed inward and the pressure released the fluid will be sucked into the bulb, in the 100 well known manner. The fountain is then attached to the pen, the fitting being made air tight. The pen is held vertical or inclined and the fluid gravitates from the fitting, through the tube 6, into the chamber 105 15, and thence through the tube 9, into the chamber 16, and thence through the channel 14, in the plug 13, in the nipple 10, where it is detained by the pen point 11, when the latter is in operative position. The fluid 110

then rises in the chamber 16, to above the outlet of tube 9, and, thereafter rises until the gravity of the fluid and the pressure of the confined air in the chamber, above the fluid, are equalized. The fluid then rises in the chamber 15, above the outlet of the tube 6, and, thereafter, rising until the gravity of the fluid and the pressure of the confined air in the chamber, above the liquid, are 10 equalized. The pen is then operative and may be used in the customary manner of fountain pens. When the pen point yields to the pressure of the operator, the fluid in the channel 14, oozes along the pen point and 15 wastes in the usual manner, the waste being immediately and instantaneously supplied by the fluid in chamber 16, the latter being replenished from the fluid in chamber 15, and it in turn replenished by the fluid in the 20 fountain. The contending forces involved in gravitation of the fluid and the back pressure of the air in the chambers provide extreme sensitiveness to the waste of the fluid and automatic restoration of equilibrium in 25 the contending forces. The fluid wasted at the pen point may be in greater or less degree, as in the case of light or heavy writing, the loss being automatically and instantaneously supplied by the fountain in the 30 manner described.

Having described my invention what I claim is—

A pneumatic fountain pen, consisting of a fountain having a body of fluid therein, a ventless chamber associated with said fountain and having a fluid body therein and provided with a duct communicating with the fountain, the lower end of said duct being normally immersed in the fluid in the chamber to subject the air in the chamber 35 to the pressure of the fluid, a ventless chamber associated with said first mentioned chamber and having a fluid body therein and provided with a duct communicating with the first mentioned chamber, the lower end 40 of said duct being normally immersed in the fluid in the chamber to subject the air in the chamber to the pressure of the fluid in the first mentioned chamber, a nipple associated with said last mentioned chamber and having a channel communicating with said last 45 mentioned chamber, and a pen point supportingly engaged by said nipple and adapted to yield to waste the fluid in the fountain pen.

Kansas City, Mo., April 22nd, 1918.

JOSEPH F. GARDNER.
